(57) **CLAIM**

The ornamental design for a game pouch, as shown and described.

DESCRIPTION

FIG. 1 is a perspective view of a game pouch showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right end view thereof; and,

FIG. 7 is a left end view thereof.

The characteristic feature of the design resides in the fact that the pouch simulates a banana.

The broken line showing in FIG. 1 is for illustrative purposes only and forms no part of the claimed design.
